UNITED STATES PATENT OFFICE.

ARTHUR ROCHE, OF NEWPORT, RHODE ISLAND.

LUNCH-BOX.

1,071,797.

Specification of Letters Patent.

Patented Sept. 2, 1913.

Application filed June 26, 1912. Serial No. 705,953.

To all whom it may concern:

Be it known that I, ARTHUR ROCHE, a citizen of the United States, residing at Newport, in the county of Newport and 5 State of Rhode Island, have invented certain new and useful Improvements in Lunch-Boxes, of which the following is a specification.

My invention relates to improvements in 10 lunch boxes, and refers particularly to a workman's or laborer's lunch box, one object being the production of a box which will conveniently and separately accommodate the food, eating utensils, such as knife, fork, 15 and spoon, and the beverage, in order that a sanitary and convenient article of this character will be provided.

Another object of my invention is the provision of a lunch box which will be of 20 small and compact size and at the same time have ample space for the purpose; which will protect the contents and permit ready access; and which can be produced at a small price, insuring a desirable and practical 25 lunch box for the desired purpose.

To attain the desired objects, the invention consists of a lunch box embodying novel features of construction and combination of parts, substantially as disclosed herein.

30 Figure 1 represents a perspective view of the lunch box closed. Fig. 2 represents a similar view with the hinged member thrown back, or the box open. Fig. 3 represents a detail view of the division wall or partition.

Referring by numeral to the drawings, in which similar numerals of reference denote corresponding parts in the several views:— The numeral 1 designates the front wall or 40 section of the box, which is formed with the bottom 2 and the short vertical flap 3 which forms a part of the rear vertical wall, and to the vertical flap 3 by means of the hinge connection 4, is joined the hinged section or member which provides the rear vertical wall 5, the top wall or cover 6, and the vertical overlapping flange or flap 7, which is formed with an opening 8, to engage the spring catch or keeper 9, mounted in the 45 front wall of the box. From this construction, it will be noted that the main portion of the box consists of the section forming the front wall, bottom and flap forming a part of the rear wall, and the hinged member which provides the rear wall, top or

cover, and securing flap, thus producing a very simple, cheap and durable construction, and the edge 10 of the hinged section is crimped and incloses the continuous reinforcing or strengthening wire 11, which extends entirely around the hinged member forming the keeper engaging portion 12, as well as the pintle or hinge rod 13. Also the edge 14 of the rigid section is crimped and interlocks with the bent edge or flange 15 of the vertical end walls 16, thus making a complete box receptacle of great strength and within the box or food chamber at a suitable place is the vertical division wall 17, provided with tongues 18, which engage 70 slits 19, and being bent serve to retain the division wall in place. This division wall thus provides in the box a food chamber 20, and a beverage containing chamber 21, in which a bottle or jar will nicely fit, and the 75 vertical division wall 17 is of sufficient height to permit its upper portion to be bent or shaped to provide the receptacle or compartment 22, to receive knife, fork, and spoon and the material 23 around the top or 80 edge is bent to receive the strengthening wire 24, which passes entirely around the top of the box.

The box is provided with the flat handle 25, mounted in the top and having a sliding movement to close against the top when not in use.

It will thus be seen that my box provides three chambers or compartments which are separate and in which may be placed the 90 food, the eating utensils, and the bottle carrying the beverage, the short flap forming a part of the rear wall also serving to retain the bottle in placing and preventing it from movement or falling out, and that a 95 convenient and sanitary box is provided.

It will also be apparent that while the box stores and preserves the contents in a clean and sanitary condition; it separates the food and makes the articles easily accessible 100 when needed; and also that the box can be made of any desired size and will prove efficient and practical in every particular.

I claim:—

1. A receptacle, comprising a rigid and a 105 hinged section, a vertical divisional wall secured in the rigid section by means of integral tongues projected therefrom, said wall being bent over upon itself and thence outwardly at right angles to provide a hori- 110

zontally disposed ledge and terminating in an upwardly bent wall formed with a flange for engagement with the edge of the rear wall of the rigid section, whereby a large 5 deep receptacle or compartment, a narrow shallow compartment, and a narrow deep compartment are provided.

2. A lunch box, consisting of the rigid member forming the front, bottom, and rear vertical flap, the member hinged to said flap and forming the rear wall, top, and retaining flap, the keeper on the front wall engaging said flap, the end walls, and the division wall secured to the end wall and bottom and formed with a horizontal receptacle, the edge being crimped and containing a strengthening wire and the end walls and rigid member being connected by an interlocking bend along their edges.

29 3. A lunch box, consisting of the rigid member forming the front, bottom, and rear vertical flap, the member hinged to said flap and forming the rear wall, top, and retaining flap, the keeper on the front wall 25 engaging said flap, the end walls, and the division wall secured to the end wall and bottom and formed with a horizontal recep-

tacle, the hinged member being formed with a surrounding crimped edge, a wire inclosed in said crimped edge forming a strengthening medium, and a rod for hinging the cover to the flap along its upper edge, and a catch on the front flap of the cover formed by the wire and a contiguous opening to engage the keeper on the front wall.

35 4. A lunch box, consisting of the rigid member forming the front, bottom, and rear vertical flap, the member hinged to said flap and forming the rear wall, top, and retaining flap said flap having an opening, a keeper on the front wall engaging the opening on said flap, the end walls, the hinged member being formed with a surrounding crimped edge, a wire inclosed in said crimped edge forming a strengthening me- 45 dium, and a rod for hinging the cover to the flap along the upper edge of said flap.

In testimony whereof I affix my signature in presence of two witnesses.

ARTHUR ROCHE.
